(57) **CLAIM**

The ornamental design for “sheet label”, as shown and described.

DESCRIPTION

FIG. 1 is a front view of a sheet label, showing my new design, according to one embodiment;
FIG. 2 is a back view of the sheet label shown in FIG. 1;
FIG. 3 is a front view of a sheet label, showing my new design, according to a second embodiment;
FIG. 4 is a back view of the sheet label shown in FIG. 3;
FIG. 5 is a front view of a sheet label, showing my new design, according to a third embodiment;
FIG. 6 is a back view of the sheet label shown in FIG. 5;
FIG. 7 is a front view of a sheet label, showing my new design, according to a fourth embodiment; and,
FIG. 8 is a back view of the sheet label shown in FIG. 7. The broken lines illustrate boundaries which form no part of the claimed design. In FIGS. 1, 3, 5, and 7, the portions between the outer broken line and inner broken line form no part of the claimed design. In FIGS. 2, 4, 6, and 8, the portions within the broken line form no part of the claimed design.
